Elomir J. Key of Lowell, Mass assignor to
The Lowell Manufacturing Company
Letters Patent No 1668 - Dated Nov 11th 1862.

The schedule referred to in these Letters Patent and making part of the same
To all whom it may concern.

Be it known that I, Elomir J. Key, of Lowell, in the County of Middlesex and State of Massachusetts, have originated and designed a new Pattern for Carpets or other fabrics, of which the following is a full, clear and exact description, reference being had to the accompanying drawings, making part of this specification.

A and B, when matched, from a group, consisting of a flower, leaves and berries, resting on a plain ground which is enclosed by the lace work, I. I.

By matching figs 2 and 3, another group is formed, consisting of a large flower, leaf and fruit, resting on a plain ground enclosed by lace work C. C.

The band D., in the centre of which is a vine, runs throughout the design and forms frames enclosing the principal figures. This band supports the blocks 4, 5, 6, 7.

The colors employed for the different portions of the design,
